UNITED STATES PATENT OFFICE.

GEORGE A. TEELING, OF WORCESTER, MASSACHUSETTS, ASSIGNOR TO CARLING TURBINE BLOWER CO., OF WORCESTER, MASSACHUSETTS, A CORPORATION OF MASSACHUSETTS.

STEAM-STRAINER.

1,297,978.

Specification of Letters Patent. Patented Mar. 18, 1919.

Application filed December 10, 1918. Serial No. 266,128.

To all whom it may concern:

Be it known that I, GEORGE A. TEELING, a citizen of the United States, residing at Worcester, in the county of Worcester and 5 State of Massachusetts, have invented certain new and useful Improvements in Steam-Strainers, of which the following is a specification.

This invention relates to a specific construction of means for abstracting from steam, as received from the boiler, any foreign particles, such as bits of packing, scale, sediment, rust, etc., so that the steam passing through the device will be freed from 10 such particles or foreign matter as might tend to injure or clog the nozzles or blading of steam turbine rotors. Various differently constructed devices have been heretofore devised for the purpose of separating particles 15 of foreign matter from steam; therefore it is not intended to include, broadly, devices of substantially different construction as within the scope of the invention herein claimed.

25 The object of my present invention is to provide a practical, desirable and efficient steam straining appliance of peculiar compact construction; simple and economical for manufacture; conveniently applicable to 30 use, adapted for a straight away connection with the steam conducting pipes; and requiring but a comparatively small space for its occupancy in practice.

These objects I attain by the peculiar construction illustrated in the drawings and 35 hereinafter explained in detail.

In the accompanying drawings, Figure 1 represents an elevation view of my improved steam strainer. Fig. 2 is a longitudinal central section of the same. Fig. 3 is a top end view; and Fig. 4 is a transverse horizontal section at line X X on Fig. 2.

This improved steam strainer consists of a straight hollow cylindrical body-shell 2 of 45 cast metal (preferably bronze) of the required thickness; each of its ends being somewhat reduced or curved inward, as at 3, and provided with an integral wrench-receiving hub or polygonal end portion 4, having the inlet opening 5 and outlet opening 6 therein in coincident alinement with the axis of the body cylinder; said opening being internally threaded for the reception of

the screw-threaded ends of steam pipes 1 and 0. The openings are preferably of the same dimension at each end of the body.

Within the body cylinder 2 and cast integral therewith, at a position somewhat above the lower end of the chamber, there is a pocket or receptacle 10, preferably of quadrant shape and of less diameter than the interior of the body. The mouth of said pocket is open at the top and is provided with an annular ledge 7 and surrounding lip or rim 9 axially and diametrically approximately coinciding with the opening 5 in the upper end of the shell. The lower end of said pocket has a clean-out opening 8 that extends laterally outward through a suitable boss 12 at the side of the cylinder, and is closed by a removable screw-threaded stopper or plug 13, fitted therein and adapted to be turned by a wrench; or if preferred by a thumb piece formed upon the stopper. The clean-out opening may be nearly the size of the interior diameter of the pocket.

Ample clearance space 15 for the flow of steam is provided between the wall of the pocket and the cylindrical shell 2, and a full circular chamber is provided below the pocket and adjacent the outlet opening 6.

A cylindrical tubular strainer 16 formed of perforated or foraminated sheet metal (preferably bronze) or other suitable screen material, is arranged between the lower part 85 of the upper end opening 5 and the top of the sediment pocket 10. The diameter of said strainer cylinder is of such dimension as will pass through the threaded opening 5 and fit within the rim 9 of the pocket, its 90 lower end seating upon the ledge 7, while its upper end fits the opening 5, or within the bore of a circular flange 17 formed on the interior of the shell, just below the end of the screw-threaded portion. The opening 5 in the shell may be bored or reamed out with a tool of the required size, the end of which is suitably formed and adapted to extend down to the pocket for dressing off the face of the ledge 7 and interior of the rim 9. 95 The strainer 16 can be readily inserted and withdrawn through the threaded opening 5, but is retained securely in its proper position when the end of a steam pipe 1 is screwed into the shell, as when the device 100 is attached for service.

Sufficient annular space 20 is provided between the strainer cylinder 16 and the interior of the body cylinder 2, so that steam can freely pass through the strainer at all 5 sides thereof.

In the operation, the steam flows directly from the end of the supply pipe I into the top end of the strainer cylinder 16, in a manner to project any sediment of foreign 10 substance into the pocket 10 while the steam passes laterally through the perforated strainer cylinder into the annular space 20, between the strainer and shell 2, and thence to the outlet opening 6 and pipe O connected 15 thereto. Should any sediment lodge upon the strainer the inflow of steam tends to drive it therefrom into the pocket.

This device is applicable for straining other elastic fluids than steam. It is especially useful in connection with elastic-fluid 20 turbine motors for protecting the nozzles and bladings from becoming clogged, or injured by accumulations of grit and sediment.

25 This steam strainer device is so designed and organized that the steam inlet and steam outlet are in axial alinement with the cylindrical body-shell, the axis of the tubular strainer and the mouth of the sediment 30 pocket; thus forming a straight-away connection with the steam pipes at either end, so that the steam flow is practically in one direction; thereby eliminating unnecessary loss incident to turns and bends. The 35 strainer tube is self cleaning; foreign matter coming in with the steam is discharged downward as the steam passes laterally through the apertures of the strainer, therefore the particles can not stay in suspension 40 to clog the holes of the strainer, since the velocity through the holes of the strainer tube is so low in comparison with the entrance velocity of the steam that the foreign matter must deposit in the receiving pocket. 45 Deposited matter may be removed from the pocket upon removal of the clean-out stopper 13, and may be positively and quickly ejected by allowing steam to pass through so as to blow out the collected material. The body-shell being of comparatively 50 small dimension, and of the form shown, can be conveniently connected with steam pipes where the adjacent space is limited, or in close relation to other obstructions.

Copies of this patent may be obtained for five cents each, by addressing the "Commissioner of Patents, Washington, D. C."

What I claim is:—

1. A steam strainer consisting of a hollow cylindrical body having an inlet and outlet in its ends respectively in axial alinement, said body provided internally with an integral pocket having a concentric upper opening and seat, its lower end extending through the side of the body and closed by a removable stopper, and an interior perforated tubular screen extending from the inlet-opening to the top of said pocket, with an annular space within said body surrounding said screen and communicating with the outlet opening. 55

2. In a device of the class specified, a straight cylindrical body-shell inwardly curved at its ends and provided with wrench-receiving hubs having inlet and outlet openings screw-threaded for attachment to pipes in coinciding axial alinement, said body provided internally with a sediment receptacle formed integral therewith and opening laterally through the side of the body cylinder, the mouth of said receptacle having an annular ledge and rim-flange concentric with the body-shell, a tubular strainer passable through the inlet opening and disposed with its lower end fitting within said rim-flange and supported upon said ledge at the mouth of said receptacle, the upper end of the strainer fitting within the bore of a flange at the top end opening of the body, said strainer being axially in alinement, therewith. 75

3. In a device for the purpose specified, a cast metal shell consisting of a cylinder having polygonal hubs at its ends each with a screw-threaded opening therethrough, said shell internally provided, at a position somewhat above its lower end, with an integrally formed quadrant-shaped pocket having an upwardly directed mouth and annular seating-rim approximately corresponding in size and in coincident axial alinement with the end openings, the lower end of said pocket opening through the side of the cylinder and provided with a screw-threaded stopper, and an internal foraminated cylinder having its respective ends supported by said seating-rim and within the inlet opening axially concentric with the main cylinder. 95

Witness my hand this seventh day of December, 1918.

GEORGE A. TEELING.
